(57) **CLAIM**

The ornamental design for a biomonitoring interface device, as shown and described.

DESCRIPTION

FIG. 1 is an isometric view, from the top, of the biomonitoring interface device.

FIG. 2 is an isometric view, from the bottom, of the biomonitoring interface device.

FIG. 3 is a plan view of the top of the biomonitoring interface device.

FIG. 4 is an elevation view of the right side of the biomonitoring interface device.

FIG. 5 is an elevation view of the front of the biomonitoring interface device.

FIG. 6 is a plan view of the bottom of the biomonitoring interface device.

FIG. 7 is an elevation view of the back of the biomonitoring interface device; and,

FIG. 8 is an elevation view of the left side of the biomonitoring interface device.

1 Claim, 3 Drawing Sheets
